UNITED STATES PATENT OFFICE.

SIDNEY H. PEAT AND JOSEPH B. JOHNSTON, OF KANSAS CITY, MISSOURI.

DESIGN FOR A STATUETTE.

58,397.

Specification for Design.

Patented July 12, 1921.

Application filed March 22, 1918. Serial No. 224,079. Term of patent 3½ years.

To all whom it may concern:

Be it known that we, SIDNEY H. PEAT and JOSEPH B. JOHNSTON, citizens of the United States, residing at Kansas City, in the county of Jackson and State of Missouri, have invented a new, original, and ornamental Design for Statuettes, of which the following is a specification, reference being had to the drawing, forming part thereof.

In the figure we have shown a perspective of a statuette embodying our design.

We claim:

The ornamental design for a statuette as shown.

SIDNEY H. PEAT.
JOSEPH B. JOHNSTON.
